US0D1049788S

(12) **United States Design Patent** (10) **Patent No.:** **US D1,049,788 S**
(45) **Date of Patent:** **** Nov. 5, 2024**

(54) **INSULATED BAG**

(71) Applicant: **Hong Kong Honchang Technology Co., Limited**, HongKong (CN)

(72) Inventor: **XueYing Ji**, HongKong (CN)

(**) Term: **15 Years**

(21) Appl. No.: **29/861,304**

(22) Filed: **Nov. 29, 2022**

(51) LOC (14) Cl. **07-10**

(52) U.S. Cl.

USPC **D7/607**

(58) **Field of Classification Search**

USPC D7/300.1, 500, 507, 510, 511, 542, D7/543–545, 549, 550.1, 554.4, 552.1, D7/553.1, 553.2, 553.6, 553.7, 554.2, D7/555, 556, 557, 565, 584, 586–587, D7/601, 602, 605, 607; D9/715, 716, D9/719, 738, 741, 743–745, 516, 530, D9/537–538; D3/273, 276, 283, 284, D3/285, 287, 289, 327; D24/231, 232; D19/65, 75, 81, 83, 92, 95, 102, 103

CPC F25D 2331/801; F25D 3/08; F25D 3/06; B65D 1/34; B65D 1/36; B65D 1/2046; B65D 23/02; B65D 23/12; B65D 29/00; B65D 29/02; B65D 29/04; B65D 41/4014; B65D 81/3858; B65D 81/3823; B65D 81/3888; B65D 81/3897; B65D 81/18; B65D 31/04; B65D 69/00; B65D 81/3841; A45C 11/20; A45C 13/02; A45F 3/04; A45F 3/02; A45F 3/12; A45F 3/14; A47G 19/02; A47G 19/025; A47G 19/027; A47G 19/03; A47G 23/06; A47G 23/0608

(57) **CLAIM**

The ornamental design for an insulated bag as shown and described.

DESCRIPTION

FIG. 1 is a perspective view of an insulated bag showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

1 Claim, 8 Drawing Sheets
